ATOMIZER FOR PERFUME AND LIKE LIQUIDS

Hobart A. Simpson, Valley Stream, and Alfred A. Bamberger, Flushing, N. Y.

Application August 18, 1948, Serial No. 44,814

16 Claims. (Cl. 299—88)

1

This invention relates to atomizers for perfume and like liquids.

An object of this invention is to provide an atomizer formed with a pump chamber and a liquid chamber parallel thereto, one end of the liquid chamber being formed with an air opening communicating with the plunger chamber, with a vent and with a liquid supply opening, a rotary head mounted for rotation on said end of said liquid chamber and provided with an air opening vent, and a liquid nozzle adapted, on one angular position of said rotary head, to communicate with said air opening, vent and liquid opening of said liquid chamber, a piston or plunger within the pump chamber, rotary means on said atomizer, releasably retaining said plunger against reciprocating movement and adapted to release said plunger for reciprocatory movement upon rotating said rotary means, means to interconnect the rotary means with the rotary head for rotating said rotary head upon rotating said rotary means, whereby to register the air passage, vent and liquid nozzle of the rotary head with the air opening, vent and liquid opening of the liquid chamber when the rotary means is moved to plunger releasing position, and for mis-aligning the air opening, vent and nozzle of the rotary head with respect to the air opening, vent and liquid opening of the liquid chamber for closing the latter when said rotary means is rotated to plunger retaining position.

Another object of this invention is to provide in an atomizer of the character described, a plunger provided with a cup-shaped pump or plunger gasket and a ring-shaped coil spring within the gasket pressing the outer wall of the gasket outwardly against the inner surface of the pump chamber to maintain good frictional contact.

Yet another object of this invention is to provide in an atomizer of the character described, a body formed with an opening, a liquid chamber within said opening, said liquid chamber comprising a cylindrical member formed with a top wall, said top wall being formed with an air passage, and the outer surface of said cylindrical member being formed with a longitudinal slot communicating at one end with said passage, and said body being provided with an air pump chamber, the wall between the first mentioned opening and the pump chamber being formed with passage interconnecting the lower end of the slot with the lower end of the pump chamber.

Still a further object of this invention is to provide an atomizer of the character described,

2

formed with a pair of parallel openings, a pump plunger mounted for reciprocation in one opening, a liquid chamber fixed with the other opening, a ring mounted for rotation at the upper end of the pump chamber, a rotary head rotatably mounted at one end of the liquid chamber, and a link intercommunicating the ring with the rotary head whereby rotation of the ring will cause rotation of the head, and means to limit rotary movement of the head in opposite directions.

Another object of this invention is to provide an atomizer of the character described, comprising a body formed with a pump or plunger chamber extending to the upper end of the body, a plunger mounted for reciprocation in said chamber, a ring rotatably and non-slidably mounted on said body at the upper end of the plunger chamber, a pin of said plunger movable through a slot in said ring, and said ring being rotatable to engage said pin for retaining said plunger down against upward movement until said ring is rotated to bring the slot into alignment with said pin, and a spring being provided at the bottom of the plunger chamber to raise the plunger when said pin is in alignment with said ring.

Still another object of this invention is to provide in an atomizer of the character described, a body formed with a plunger opening extending to the upper end of the body, a plunger comprising a piston and a piston rod, mounted for reciprocation in said chamber, a spring in the bottom of the chamber interposed between the bottom of the chamber and the plunger, a plunger guide fixed to the body and formed with an opening through which the piston rod passes, a ring mounted for rotation on the body, means on said guide to retain the ring against sliding movement, said ring being formed with a slot, an offset pin on the piston rod adapted to pass through the slot in said ring, and said ring being adapted for rotation to engage the said pin for holding the piston against movement, and a button or knob at the upper end of the piston rod for pressing down the plunger.

Still another object of this invention is to provide a strong, rugged, durable and compact pocket atomizer of the character described, which shall be relatively inexpensive to manufacture, which shall be easy to manipulate, which will be leak-proof, and yet practical and efficient to a high degree in use.

Other objects of this invention will in part be obvious and in part hereinafter pointed out.

The invention accordingly consists in the features of construction, combinations of elements, and arrangement of parts, which will be exemplified

fied in the construction hereinafter described, and of which the scope of invention will be indicated in the following claims.

In the accompanying drawings in which is shown various illustrative embodiments of this invention,

Fig. 1 is a longitudinal, vertical cross-sectional view through an atomizer embodying the invention, and showing the plunger depressed, and the rotary head and plunger retaining ring in condition to permit the atomizer to be operated for atomizing liquid;

Fig. 2 is a cross-sectional view taken on line 2—2 of Fig. 1;

Fig. 3 is a bottom plan view of the atomizer;

Fig. 4 is a cross-sectional view taken on line 4—4 of Fig. 2;

Fig. 5 is a cross-sectional view taken on line 5—5 of Fig. 1;

Fig. 6 is a cross-sectional view taken on line 6—6 of Fig. 1; and

Fig. 7 is a cross-sectional view taken on line 7—7 of Fig. 1.

Referring now in detail to the drawing, 10 designates an atomizer embodying the invention. The same comprises a body 11 which may be made of a single piece of metal. Body 11 has a bottom surface 12, a top surface 13, parallel front and rear faces 14 and 15, and symmetrical semi-cylindrical end faces 16 and 17. The bottom and top faces 12 and 13 are parallel to one another. The body is formed with a drilled opening or bore 18, extending from the bottom surface 12, upwardly and terminating in an upper surface 19, somewhat below the top surface 13. The axis of the bore is at the axis of the semi-cylindrical surface 16, but the radius of the bore 18 is somewhat less than the radius of surface 16, thereby forming a semi-cylindrical wall 20, surrounding half of the bore, as shown in the drawing. Said wall 20 is formed with a round drilled opening 21, below surface 19, the axis of the opening 21 passing through the axis of the bore 18.

Said body 11 is furthermore counterbored at its upper end, as at 22, forming an inner substantially semi-cylindrical surface 23, concentric with the axis of semi-cylindrical wall 17, down to a depth just below the axis of opening 21, and a radius substantially similar to the radius of said surface 17, and forming a top flat annular surface 24. Said body is also formed with a bore 25 at the axis of said surface 17, and extending downwardly from the surface 24, to a point spaced above the bottom surface 12. The diameter of the bore 25 is less than the diameter of surface 17, leaving a semi-cylindrical wall 26 partially surrounding said bore. The bores 18 and 25 are parallel to one another, and while the bore 18 is open at the bottom, the bore 25 is open at its upper end. Between the bores 18 and 25, is a web or wall 27. Said wall 27 is formed with a drilled opening 28, which inclines upwardly from bore 18 to bore 25. The opening or passage 28 is located in a plane passing through the axes of the bores 18 and 25, and interconnects the bore 18 above its lower end, with the bore 25, likewise, somewhat above the lower end of the latter. The inclination of bore 28 is such, that a drill may be passed through the lower end of bore 18 to effect a drilling operation for the opening 28.

The body 11 is furthermore formed with a horizontal drilled opening 30 interconnecting the upper end of bore 18 with the inwardly curved part-cylindrical surface 23. Said opening 30 is offset from a plane passing through the axes of

the bores 18 and 25, and is tangent to the plane of surface 24 lying wholly above said plane. The opening 30 is a round opening and it is also substantially tangent to the bore 18, as shown in Fig. 2 of the drawing. It will be noted that at the ends of the part-cylindrical surface 25 are vertical edges 23a and 23b, but the sharp edges are preferably removed.

Fixed within the bore 18 is a liquid or perfume chamber 32. Said chamber has a cylindrical wall 33 open at its lower end, and is formed at its upper end with an end wall 34. The end wall 34 has a flat upper surface 35 located below the opening 21. The lower end edge 36 of the cylindrical wall 33 is located above the lower surface 12 of the body. The outer surface of the cylindrical wall 33 is grooved annularly, as at 37, between its upper and lower ends to reduce the amount of surface contact between chamber 32 and the inner surface of bore 18. The outer surface of cylindrical wall 33, furthermore is formed with a longitudinal slot 38 communicating at its lower end with passage 28. The slot 38 terminates short of the upper end of chamber 32, as shown in Fig. 1 of the drawing. The end wall 34 is formed with an upwardly and inwardly inclined through opening 39 communicating at its outer end with the upper end of slot 38. Said end wall 34 is also formed in its upper surface with a downwardly extending opening 40, communicating with the upper end of opening 39. It will be noted that the opening 40 is offset from the axis of chamber 32.

Said end wall 34 is also formed with a vertical through-drilled opening 41. The openings 40 and 41 are located in a plane passing through the axes of bores 18 and 25, and on opposite sides of the axis of bore 18. The opening 41 communicates with the interior of the chamber 32.

End wall 34 is also formed with a drilled vertical through-opening 42, offset from the axis of bore 18, and located in a plane at right angles to the plane of the axes of bores 18 and 25.

The lower end of cylindrical wall 33 is formed with internal screw threads 44 for the purpose hereinafter appearing.

Means is provided for closing the lower end of the liquid chamber 32. To this end, there is screwed to the lower threaded end 44 of the liquid chamber, a screw cap 45. Cap 45 has an external threaded portion 46 engaging the internal threads 44. Said cap also has an annular flange 47 having an external diameter, substantially equal to the internal diameter of bore 18. The cap is under-cut, as at 48, to receive a washer or gasket 49 interposed between the flange 47 and the lower end edge 36 of the chamber 32. It will now be understood that the chamber 32 is closed by the cap 45.

The cap 45 may be formed with a slot 50, at its lower end to receive a screw driver or an edge of a coin, so that the cap may be unscrewed or screwed into place.

The chamber 32 may be filled with perfume, or other liquid to be atomized and sprayed. Said chamber is preferably press-fitted into the bore 18, so that it will remain fixed in place.

Force-fitted into opening 41 of the end wall 34 is the upper end of a liquid or perfume tube 52. The tube 52 projects downwardly to a point just above the screw cap 45. The lower end of the tube is open, as is also its upper end. The upper end of the tube 52 may be flush with the surface 35. Liquid to be sprayed will rise in the tube 52, as will appear hereinafter.

Mounted for rotation within the upper end of

the bore 18, and between the liquid chamber 32, and the upper surface 19 of the bore, is a rotary jet, or valve member or head 55. Member 55 has a cylindrical outer surface 56, and a flat top surface 57. In its upper surface it is formed with a central shallow bore or opening 58. At its upper end, the rotary member 55 is also formed with a cut-away portion 59, forming a flat vertical rectangular surface 60 extending down substantially to the axis of opening 21 and offset from the axis of the rotary member. At the lower end of surface 60 is a flat horizontal surface 61. Said horizontal surface 61 is formed with an opening 62 which may extend down through to the lower end of the rotary member. At the lower end of the rotary member is a shallow recess 63, and at the periphery of the recess is an upwardly extending annular groove 64 leaving an annular rim edge 65 which is turned inwardly to clamp a gasket 66 against the recess surface, the outer edge of the gasket being pressed into the groove 64. The gasket 66 contacts the upper surface 35 of the chamber 32. The gasket is made of "Neoprene" or the like material, and is formed with openings 67, 68 and 69, adapted to register, in one angular position of the rotary member 55, with the openings 40, 41 and 42, respectively, of the liquid chamber 32. It will be noted that the gasket 66 is tightly clamped to the rotary member 55, and will rotate therewith, and when the rotary member is rotated to a position misaligning openings 67, 68 and 69 with respect to the openings 40, 41 and 42, respectively, said latter openings will be closed and sealed by said gasket. The gasket may be selected of any suitable material which will not deteriorate or be affected by alcohol, or by the perfume or liquid within the chamber 32.

The rotary member 55 is formed with a radial drilled spray opening 70 co-axial with opening 21 and of somewhat smaller diameter than said opening 21, and terminating short of the axis of said rotary member. It will be noted that the surface 60 is inclined rearwardly and inwardly with respect to the front and rear surfaces 14, 15. The rotary member 55 is furthermore formed with a vertical drilled opening 71 extending upwardly from the lower recessed surface 63, and communicating with the bottom of the opening 70. The opening 71 registers with the opening 68 in the gasket 66, and hence will register in one position of the rotary member with the tube 52. The inner wall 72 of the opening 70 is flat, annular, and in a plane perpendicular to the surfaces 14 and 15 of the body in the position of the rotary member when the openings 67, 68 and 69 register with the respective openings in the upper end wall 34 of the chamber 32.

The rotary head 55 is furthermore formed with an upwardly inclined drilled opening 74 extending from the recessed surface 63 of the head to a point close to said surface 72. Passage 74 is connected to surface 72 by an opening 75. The opening 75 is in the plane of the axes of the rotary member 55 and opening 70. The lower end of passage or opening 74 communicates with opening 67 in the gasket. Said rotary member 55 is furthermore formed with a vertical through-opening 77 extending from the lower recess surface 63 to the top surface 57 of the rotary member and registers with the opening 69 in the gasket 66. Fixed within the opening 71 is a nozzle or jet tube 78 projecting upwardly into the opening 70. The lower end of the tube 78 is flush with the surface 63. The upper end of the nozzle or tube is formed with a restricted opening. The

upper end of said nozzle, furthermore, is substantially at the axis of the opening 70, and hence close to the axis of the opening 75.

It will now be understood that when the rotary member 55 is in the position shown in Fig. 1, with the openings 67, 68 and 69 registering with the openings 40, 41 and 42, respectively, air may pass from the bore 25 through passage 28, through slot 38, passage 39, opening 40, opening 67, passage 74, and opening 75. When air is forced through said openings and passages, the air will blow across the mouth of the nozzle 78. Liquid passing upwardly from the interior of chamber 32 through tube 52, opening 68, and tube 78 will be atomized by the stream of air coming out through the opening 75. The openings 42, 69 and 71 serve as an air vent to permit entry of air into the chamber 32 as the liquid is used up.

When the rotary head is rotated, the openings 40, 41 and 42 are sealed, and the opening 70 becomes misaligned with respect to the openings 21, and is, hence, likewise closed. The means for rotating the rotary head 55 will be explained hereinafter.

Means is provided to press the rotary member 55 and its gasket 66, down against the upper surface 35 of the chamber 32. To this end, there is received in the opening 58, a pin 79, headed at its lower end as at 79. Interposed between the flange 79 and inner surface 19 is a coil compression spring 80. The spring 80 is of varying diameter, its smaller end engaging the flange 79, and its large end engaging the surface 19. The spring 80 serves to depress the rotary member, and its gasket against the liquid chamber to insure a good seal.

Means is provided to pump air from the lower end of the bore 25 to passage 28 and hence, through slot 38 for atomizing liquid passing upwardly through the nozzle 78. To this end, there is mounted for reciprocation, within the pump chamber 25, a pump or plunger 85. The same comprises, generally, of a piston 86 attached to the lower end of a piston rod or shaft 87, provided with a knob or button 88 at its upper end. The shaft 87 comprises a portion 89 of polygonal cross-section, here shown for the purpose of illustration, as hexagonal. At the lower end of portion 89 is a stem 90 of reduced size, and cylindrical externally. The stem 90 is formed with a hollow socket 91 at its lower end. Between portions 90 and 89, is an under-shoulder 92. At the upper end of said portion 89 is an externally threaded, reduced axial stem 93 forming a shoulder 94 between portions 89 and 93. Below the shoulder 94, portion 89 is formed in one of its faces with a horizontal blind opening 95, for the purpose hereinafter appearing.

The piston 86 is fixed on the stem 90. It comprises a metal disc 95a formed with a central opening through which the stem 90 passes, and said disc contacts the under-shoulder 92. Contacting the underside of the disc 95a is a cup-shaped pump gasket 96 which may be made of leather, synthetic plastics, or other suitable material. The gasket 96 has a flat top wall 97 and a skirted downwardly extending wall 98 frictionally contacting the inner surface of the bore 25. Top wall 97 has a central opening through which the stem 90 passes. Disposed within the cup 98 and fixed onto the lower end of stem 90, is a piston clamp member 100. The member 100 has a top, flat annular wall 101 from which extends downwardly, a tubular wall 102 surrounding the stem 90. Wall 101 contacts the underside of top wall

97 of the gasket 96. At the lower end of tubular wall 102, is a conical shaped wall 103 having a flat undersurface. The lower end of tubular portion 94 is riveted over against the flat undersurface of portion 103, as at 104, thereby keeping members 95, 96 and 100 in clamped assembled relation with the lower end of the piston rod 81. The said portion 103 is formed at its outer periphery with a downwardly extending annular flange 105. Interposed between the underside of member 103 and the bottom surface 106 of the bore 25, is a frusto-conical shaped coil compression spring 107 which normally urges the plunger or pump 85 in an upward direction.

Screwed to the upper end 93 of the piston rod 89 is the knob or button 88. Said button has a top, flat, annular wall 109 and a downwardly extending central internally screwed portion 110, which is screwed to the stem 93. The diameter of wall 109 is somewhat smaller than the diameter of the surface 22. It will be noted that when the button 88 is depressed, the piston will force air downwardly through the passage 28, and when pressure is released from the button 88, the spring 107 will move the piston upwardly.

Means is provided to prevent rotation of the piston 85. To this end, there is fixed in the upper end of the bore 25, a piston or pump guide 112. Said pump guide comprises a substantially cylindrical portion 113 force fitted into the upper end of the pump bore 25. At the upper end of said portion 113, is an annular flange 114 contacting the upper surface 24. Extending upwardly from the said portion 113 is a sleeve portion 115 formed near its upper end with an external groove 116. The guide member 112 is formed with a through opening 117 of hexagonal shape to slidably receive the hexagonal piston rod 89. Said portion 113 and the sleeve 115 are formed with a through slot 118 communicating with the hexagonal through opening 117 and forms an extension thereof. The sleeve 115 thus has a slot all the way through, and the slot 118 extends beyond the sleeve, as shown in Fig. 2 of the drawing. The upper end edge 119 of sleeve 115 is disposed somewhat below the undersurface 120 of the top wall 109 of button 88. It will be understood that since the hexagonal rod or shaft 89 slidably fits within the through opening 117, the piston 85 cannot rotate, but can only reciprocate. The lower end of portion 113 may be bevelled or chamfered. Furthermore, the outer surface of portion 113 may be knurled, if desired.

Fixed in the opening 95 of the piston rod 89 is a horizontal radial pin 121 projecting into slot 118. The pin 121 is located somewhat above the upper surface 122 of the flange 114. In said upper surface 122 is a downwardly extending through hole 123 for the purpose hereinafter appearing.

Means is provided for releasably retaining the piston or pump 85 in fully depressed position, and for misaligning the rotary head 55 for sealing the openings in said head and closing opening 21 when the piston is retained in depressed condition, and for rotating the rotary head to the position shown in Fig. 1, with the openings therein aligned with the openings in the liquid chamber, and with the openings 21 uncovered, when the piston is released so that it may be reciprocated in the pump chamber for atomizing liquid. To this end, there is rotatably and non-slidably mounted on member 112, a pump ring 130. Said ring 130 comprises a cylindrical wall 131 formed with an intermediate externally knurled portion

132. Said ring is also formed with a horizontal annular web or wall 134 spaced from the upper and lower ends of wall 131. The web 134 is formed with a circular central opening 136 and with a downwardly extending part-cylindrical flange 137 projecting downwardly from the web 134. The lower edges of flange 137 and wall 131 contact the upper surface 122 of flange 114. The web 134 is formed with a slot 138 extending from the circular through opening 136 and adapted in one angular position of the ring, to register with the slot 118. The sleeve 115 passes through the opening 136, and the ring may rotate about the sleeve 115. The flange 137 is cut away as at 137a to permit rotation of the ring 130. The pin 121 is located just beneath the underside of the web 134. When the slot 138 in web 134 is in alignment with the slot 118 the piston 85 is released and may be reciprocated up and down, since the pin 121 will pass through opening 138. However, should the ring 130 be rotated in a clockwise direction, looking at Fig. 2 of the drawing, the slot 138 will become misaligned with respect to the pin, and said pin will then be engaged by the underside of the web 134 to keep the piston from rising. It will be noted that the groove 116 is located just above the upper surface of the web 134. Received in said groove, is a split spring ring 140 which contacts the upper surface of the web 134 to prevent longitudinal movement of the ring, while permitting rotation of the latter. Web 134 is formed with a through opening 141 disposed in a plane at right angles to a plane passing through the axis of the ring and bisecting slot 138. Interconnecting the ring 130 and the rotary head 55 is a link 143. Said link comprises a horizontal portion 144 passing through the opening 30 and located below web 134, and above the plane of surface 61. Extending downwardly at one end of said portion 144 is a leg 145 which rotatably engages within the opening 62 in the surface 61 of the rotary head 55. At the other end of said portion 144 is a through opening 146 registering with the opening 141. Fixed within the opening 146 is an upwardly extending pin 147 rotatably engaging within the opening 141.

It will now be understood that when the parts are in a position shown in Figs. 1, 2 and 3, the piston is released, and may be worked up and down by the thumb of the user and spring 107. The rotary head has its openings aligned with the openings in the oil chamber, and oil or perfume or liquid therefrom will be atomized, and the spray will pass through the opening 21. However, with the piston depressed to the position shown in Fig. 1 should the ring 130 be rotated in a clockwise direction, the web 134 will engage the pin 121 to retain the piston in depressed condition, and at the same time, the rotary head 55 will be rotated in a clockwise direction to mis-align opening 70 with respect to opening 21, so that part of the cylindrical surface of the rotary member will close the opening 21, and the openings 74 and 42 and the nozzle 78, will be sealed off and closed. When the user desires thereafter to use the atomizer, the ring 130 is again rotated, but in a counter-clockwise direction, for again aligning the slot 138 with pin 121, to release the piston, and thereby, also rotating the head 55 to the in-use position of Figs. 1, 2 and 3. The spring 107 will then lift the piston, and the user may then work the piston up and down for spraying or atomizing perfume from the liquid chamber. The rotation of the ring 130

in a clockwise direction is limited to a position where the link 143 contacts surface 60 of the rotary head, or one edge of flange 137 contacts pin 121.

To limit rotation of the ring 131 in a counter-clockwise direction, there is fixed within opening 123, a pin 150, which projects above surface 122. The pin is so located that one end of link 143 will contact said pin when the opening 70 is aligned with the opening 21 and the slot 138 is centered relative to the pin 121.

Means is provided to resiliently press the cylindrical gasket wall 98 against the inner surface of bore 25. To this end, there is mounted within the piston, and between walls 101 and 103 a ring shaped coil spring 86a, normally contacting and pressing outwardly against the cylindrical wall 98 of the gasket to ensure good frictional contact between the gasket and the inner surface of the bore.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings, is to be interpreted as illustrative and not in a limiting sense.

While the drawing shows the gasket 66 to be attached to the underside of the rotary valve head 55, if desired, the gasket may be attached to the upper end of the liquid chamber instead of to the rotary head. In such case, the underside of the rotary head would be smooth, and the upper end of the liquid chamber would be formed with a shallow recess to receive the gasket and with an annular groove and annular rim flange crimped in to grip the edge of the gasket and press the same with the groove.

Having thus described our invention, we claim as new and desire to protect by Letters Patent of the United States:

1. An atomizer comprising a body, a pair of parallel bores in said body, said body being formed with a passage communicating said bores, an air pump within one bore, a liquid chamber fixed within the other bore, said liquid chamber having an upper end wall, and being formed with an external slot communicating with said passage, said end wall being formed with an opening communicating with said slot and the upper surface of said end wall, said end wall being formed with a liquid-opening communicating with said liquid chamber and the upper surface of said end wall, a tube having one end fixed within said liquid opening and projecting down into the liquid chamber, a rotary head mounted within said other bore, and above said end wall, and being formed with an air passage adapted to communicate with the first opening in said end wall, and with a nozzle adapted to communicate with said tube, a ring rotatably and non-slidably mounted on said body, and having means to retain said piston against reciprocatory movement, and means interconnecting said ring and rotary head for rotating said head upon rotating said ring.

2. An atomizer comprising a body, a reciprocating air pump thereon, a liquid chamber in said body, having a liquid opening and an air opening, means to establish communication between said air opening and the pump for supply-

ing air under pressure to the air opening when the pump is reciprocated, a rotary valve head mounted for rotation in said body, and having an air passage and a nozzle, adapted to communicate with said air opening and a liquid opening, respectively, in one angular position of said rotary head, a member rotatably and non-slidably mounted on said body, means on said member to retain the pump against operation, in one angular position of said member, and to permit operation of the pump in another angular position of said member, and means interconnecting said member and rotary head for rotating the rotary head upon rotating said member, whereby to move the rotary head to a position where the air passage and nozzle are in register with the air opening and liquid opening, respectively, of the liquid chamber when said member is in position to permit operation of the pump, and to misalign said air passage and nozzle with respect to said air opening and liquid opening, when said member is in position to retain pump against operation.

3. An atomizer comprising a body, a reciprocating air pump thereon, a liquid chamber in said body, having a liquid opening and an air opening, means to establish communication between said air opening and the pump for supplying air under pressure to the air opening when the pump is reciprocated, a rotary valve head mounted for rotation in said body, and having an air passage and a nozzle, adapted to communicate with said air opening and a liquid opening, respectively, in one angular position of said rotary head, a member rotatably and non-slidably mounted on said body, means on said member to retain the pump against operation, in one angular position of said member, and to permit operation of the pump in another angular position of said member, and means interconnecting said member and rotary head for rotating the rotary head upon rotating said member, whereby to move the rotary head to a position where the air passage and nozzle are in register with the air opening and liquid opening, respectively, of the liquid chamber when said member is in position to permit operation of the pump, and to misalign said air passage and nozzle with respect to said air opening, and liquid opening, when said member is in position to retain pump against operation, said end wall of said oil chamber being formed with a vent opening, and said rotary head being formed with a vent opening adapted to register with the vent opening in the end wall when said air passage and nozzle register with said air opening and said liquid opening.

4. An atomizer comprising a body, a reciprocating air pump thereon, a liquid chamber in said body, having a liquid opening and an air opening, means to establish communication between said air opening and the pump for supplying air under pressure to the air opening when the pump is reciprocated, a rotary valve head mounted for rotation in said body, and having an air passage and a nozzle, adapted to communicate with said air opening and said liquid opening, respectively, in one angular position of said rotary head, a member rotatably and non-slidably mounted on said body, means on said member to retain the pump against operation in one angular position of said member, and to permit operation of the pump in another angular position of said member, and means interconnecting said member and rotary head for rotating the rotary head upon rotating said member, whereby

to move the rotary head to a position where the air passage and nozzle are in register with the air opening and liquid opening, respectively, of the liquid chamber when said member is in position to permit operation of the pump, and to misalign said air passage and nozzle with respect to said air opening and liquid opening, when said member is in position to retain pump against operation, said body having an opening, and said rotary head being formed with a spray opening communicating with the air passage and into which said nozzle projects, and said spray opening registering with said opening in said body when said air passage and nozzle are registering with the air opening and liquid opening of the liquid chamber, and said spray opening being misaligned with respect to opening in said body when the rotary head is in position where the air passage and nozzle are misaligned with respect to the air opening and liquid opening of said liquid chamber.

5. An atomizer comprising a body formed with a bore extending downwardly from its upper end and a second bore parallel to the first, and extending upwardly from its lower end, a cylindrical chamber fixed within the second bore and having an upper end wall and being open at its lower end, a screw cap to close the lower end of the liquid chamber, said liquid chamber being formed with a longitudinal slot, and with an air opening interconnecting the upper end of the slot with the upper surface of said end wall, said body being formed with an air passage interconnecting the lower end of the slot with the lower end of said first bore, said end wall being formed with a liquid opening communicating with said liquid chamber and the upper surface of said end wall, a tube having its upper end fixed within said liquid opening, and projecting downwardly into said liquid chamber, said end wall being formed with a through vent opening offset from the liquid opening and air opening, a rotary valve head rotatably mounted within the upper end of the first bore, and above said liquid chamber, a gasket fixed to the underside of the rotary head, and contacting the upper surface of said end wall, spring means interposed between the upper end of the rotary head and the underside of the upper end of said second bore for pressing the rotary head down against the liquid chamber, said gasket being formed with openings adapted in one angular position of the rotary head to register with the air opening, liquid opening and vent opening in said end wall, said rotary head being formed with a spray opening at one side thereof, and with an air passage interconnecting the spray opening with the opening in the gasket which registers with the air opening in said end wall, a nozzle fixed within said rotary head and projecting into said spray opening and registering with the opening in the gasket which registers with the liquid opening, and said rotary head being formed with a vent opening registering with the opening in the gasket which registers with the vent opening in said end wall.

6. An atomizer comprising a body formed with a bore extending downwardly from its upper end and a second bore parallel to the first, and extending upwardly from its lower end, a cylindrical liquid chamber fixed within the second bore and having an upper end wall and being open at its lower end, a screw cap to close the lower end of the liquid chamber, said liquid chamber being formed with a longitudinal slot, and with an air opening interconnecting the upper end of the

slot with the upper surface of said end wall, said body being formed with an air passage interconnecting the lower end of the slot with the lower end of said first bore, said end wall being formed with a liquid opening communicating with the liquid chamber and the upper surface of said end wall, a tube having its upper end fixed within said liquid opening, and projecting downwardly into said liquid chamber, said end wall being formed with a through vent opening offset from the liquid opening and air opening, a rotary valve head rotatably mounted within the upper end of the first bore, and above said liquid chamber, a gasket fixed to the underside of the rotary head, and contacting the upper surface of said end wall, spring means interposed between the upper end of the rotary head and the underside of the upper end of said second bore for pressing the rotary head down against the liquid chamber, said gasket being formed with openings adapted in one angular position of the rotary head to register with the air opening, liquid opening and vent opening in said end wall, said rotary head being formed with a spray opening at one side thereof and with an air passage interconnecting the spray opening with the opening in the gasket which registers with the air opening in said end wall, a nozzle fixed within said rotary head and projecting into said spray opening and registering with the opening in the gasket which registers with the liquid opening, and said rotary head being formed with a vent opening registering with the opening in the gasket which registers with the vent opening in said end wall, said body having an opening adapted to register with the spray opening in the rotary head, a plunger mounted for reciprocation in said first bore, and comprising a piston within said bore, and a piston rod extending upwardly therefrom, a spring interposed between the piston and the lower end of said first bore, said piston rod being of non-circular cross-section, a guide fixed within the upper end of the first bore, having a through opening and slidably and non-rotatably receiving said piston rod, a button at the upper end of the piston rod, a ring rotatably and non-slidably mounted on said guide, said ring having a slot, and a pin being fixed to said piston rod, and adapted to pass through said slot in one angular position of said ring, whereby to permit reciprocation of said plunger, said ring being adapted to engage said pin in another angular position of said ring when said plunger is depressed to retain said plunger in depressed position, and a link interconnecting said ring with said rotary head for rotating said head upon rotating said ring, whereby to align the air passage and nozzle and vent opening in the rotary head with the air opening, liquid opening, and vent opening of said liquid chamber when the ring is in position to permit reciprocation of said plunger, and to misalign said air passage, nozzle, and vent opening in the rotary head with respect to the air opening, liquid opening, and vent opening of the liquid chamber when said ring is in position to engage said pin and retain said plunger in a fully depressed condition.

7. An atomizer comprising a body formed with a bore extending downwardly from its upper end and a second bore parallel to the first, and extending upwardly from its lower end, a cylindrical liquid chamber fixed within the second bore and having an upper end wall and being open at its lower end, a screw cap to close the lower end of the liquid chamber, said liquid chamber being formed with a longitudinal slot,

and with an air opening interconnecting the upper end of the slot with the upper surface of said end wall, said body being formed with an air passage interconnecting the lower end of the slot with the lower end of said first bore, said end wall being formed with a liquid opening communicating with said liquid chamber and the upper surface of said end wall, a tube having its upper end fixed within said liquid opening, and projecting downwardly into said liquid chamber, said end wall being formed with a through vent opening offset from the liquid opening and air opening, a rotary valve head rotatably mounted within the upper end of the first bore, and above said liquid chamber, a gasket fixed to the underside of the rotary head, and contacting the upper surface of said end wall, spring means interposed between the upper end of the rotary head and the underside of the upper end of said second bore for pressing the rotary head down against the liquid chamber, said gasket being formed with openings adapted in one angular position of the rotary head to register with the air opening, liquid opening and vent opening in said end wall, said rotary head being formed with a spray opening at one side thereof, and with an air passage interconnecting the spray opening with the opening in the gasket which registers with the air opening in said end wall, a nozzle fixed within said rotary head and projecting into said spray opening and registering with the opening in the gasket which registers with the liquid opening, and said rotary head being formed with a vent opening registering with the opening in the gasket which registers with the vent opening in said end wall, said body having an opening adapted to register with the spray opening in the rotary head, a plunger mounted for reciprocation in said first bore, and comprising a piston within said bore, and a piston rod extending upwardly therefrom, a spring interposed between the piston and the lower end of said first bore, said piston rod being of non-circular cross-section, a guide fixed within the upper end of the first bore, having a through opening and slidably and non-rotatably receiving said piston rod, a button at the upper end of the piston rod, a ring rotatably and non-slidably mounted on said guide, said ring having a slot, and a pin being fixed to said piston rod, and adapted to pass through said slot in one angular position of said ring, whereby to permit reciprocation of said plunger, said ring being adapted to engage said pin in another angular position of said ring when said plunger is depressed to retain said plunger in depressed position, and a link interconnecting said ring with said rotary head for rotating said head upon rotating said ring, whereby to align the air passage and nozzle and vent opening in the rotary head with the air opening, liquid opening, and vent opening of said liquid chamber when the ring is in position to permit reciprocation of said plunger, and to misalign said air passage, nozzle, and vent opening in the rotary head with respect to the air opening, liquid opening, and vent opening of the liquid chamber when said ring is in position to engage said pin and retain said plunger in a fully depressed condition, and means to limit rotation of said ring in opposite directions.

8. An atomizer comprising a body formed with a bore extending downwardly from its upper end and a second bore parallel to the first, and extending upwardly from its lower end, a cylindrical liquid chamber fixed within the second bore and having an upper end wall and being open at its lower end, a screw cap to close the

lower end of the liquid chamber, said liquid chamber being formed with a longitudinal slot, and with an air opening interconnecting the upper end of the slot with the upper surface of said end wall, said body being formed with an air passage interconnecting the lower end of the slot with the lower end of said first bore, said end wall being formed with a liquid opening communicating with said liquid chamber and the upper surface of said end wall, a tube having its upper end fixed within said liquid opening, and projecting downwardly into said liquid chamber, said end wall being formed with a through vent opening offset from the liquid opening and air opening, a rotary valve head rotatably mounted within the upper end of the first bore, and above said liquid chamber, a gasket fixed to the underside of the rotary head, and contacting the upper surface of said end wall, spring means interposed between the upper end of the rotary head and the underside of the upper end of said second bore for pressing the rotary head down against the liquid chamber, said gasket being formed with openings adapted in one angular position of the rotary head to register with the air opening, liquid opening and vent opening in said end wall, said rotary head being formed with a spray opening at one side thereof, and with an air passage interconnecting the spray opening with the opening in the gasket which registers with the air opening in said end wall, a nozzle fixed within said rotary head and projecting into said spray opening and registering with the opening in the gasket which registers with the liquid opening, and said rotary head being formed with a vent opening registering with the opening in the gasket which registers with the vent opening in said end wall, said body having an opening adapted to register with the spray opening in the rotary head, a plunger mounted for reciprocation in said first bore, and comprising a piston within said bore, and a piston rod extending upwardly therefrom, a spring interposed between the piston and the lower end of said first bore, said piston rod being of non-circular cross-section, a guide fixed within the upper end of the first bore, having a through opening and slidably and non-rotatably receiving said piston rod, a button at the upper end of the piston rod, a ring rotatably and non-slidably mounted on said guide, said ring having a slot, and a pin being fixed to said piston rod, and adapted to pass through said slot in one angular position of said ring, whereby to permit reciprocation of said plunger, said ring being adapted to engage said pin in another angular position of said ring when said plunger is depressed to retain said plunger in depressed position, and a link interconnecting said ring with said rotary head for rotating said head upon rotating said ring, whereby to align the air passage and nozzle and vent opening in the rotary head with the air opening, liquid opening, and vent opening of said liquid chamber when the ring is in position to permit reciprocation of said plunger, and to misalign said air passage, nozzle, and vent opening, in the rotary head with respect to the air opening, liquid opening, and vent opening of the liquid chamber when said ring is in position to engage said pin and retain said plunger in a fully depressed condition, and means to limit rotation of said ring in opposite directions, said body being formed with an opening interconnecting said bores through which said link passes.

9. An atomizer comprising a body formed with

a bore extending downwardly from its upper end and a second bore parallel to the first, and extending upwardly from its lower end, a cylindrical liquid chamber fixed within the second bore and having an upper end wall and being open at its lower end, a screw cap to close the lower end of the liquid chamber, said liquid chamber being formed with a longitudinal slot, and with an air opening interconnecting the upper end of the slot with the upper surface of said end wall, said body being formed with an air passage interconnecting the lower end of the slot with the lower end of said first bore, said end wall being formed with a liquid opening communicating with said liquid chamber and the upper surface of said end wall, a tube having its upper end fixed within said liquid opening, and projecting downwardly into said liquid chamber, said end wall being formed with a through vent opening offset from the liquid opening and air opening, a rotary valve head rotatably mounted within the upper end of the first bore, and above said liquid chamber, a gasket fixed to the underside of the rotary head, and contacting the upper surface of said end wall, spring means interposed between the upper end of the rotary head and the underside of the upper end of said second bore for pressing the rotary head down against the liquid chamber, said gasket being formed with openings adapted in one angular position of the rotary head to register with the air opening, liquid opening and vent opening in said end wall, said rotary head being formed with a spray opening at one side thereof, and with an air passage interconnecting the spray opening with the opening in the gasket which registers with the air opening in said end wall, a nozzle fixed within said rotary head and projecting into said spray opening and registering with the opening in the gasket which registers with the liquid opening, and said rotary head being formed with a vent opening registering with the opening in the gasket which registers with the vent opening in said end wall, a piston comprising a cup-shaped gasket including a cylindrical wall engaging the inner surface of the first bore, and a ring shaped coil spring within said cup-shaped gasket and pressing said cylindrical wall of said cup-shaped gasket outwardly into frictional contact with said bore.

10. In an atomizer, a body formed with a bore, a plunger mounted for reciprocation therein, said plunger comprising a piston rod, a stem extending from said rod, forming a shoulder, a washer on said stem and engaging a said shoulder, a cup-shaped gasket having an end wall through which said stem passes and contacting the washer, said gasket having a downwardly extending cylindrical wall contacting the inner surface of said bore, a member having a sleeve portion surrounding said stem, and having a wall at the upper end of the sleeve contacting the underside of the end wall of said gasket, and an annular wall at the lower end of said sleeve, means to fix said member to said stem, a coil compression spring interposed between said member and the lower end of said bore, and a ring shaped coil spring surrounding said sleeve portion and pressing the cylindrical wall of said gasket against the inner surface of said bore, a liquid chamber within said body, a rotary valve comprising means to control the passage of liquid from said liquid chamber, and the passage of air from said bore and means controlled by a ring rotatably mounted on said body for rotating said rotary valve.

11. In an atomizer a body formed with a bore, a liquid chamber member fixed within the bore and having an upper end formed with a liquid opening and an air opening, a rotary valve member rotatably mounted within said bore and above the upper end of the liquid chamber member, said valve member being formed with a liquid opening and an air opening adapted, in one angular position of said rotary valve member, to be aligned with the liquid and air openings in the liquid chamber member, one of said members being formed at the end thereof adjacent the other of said members, with a shallow recess and with an annular groove surrounding said recess and with an annular flange surrounding said groove, and a gasket within said recess and said annular flange being crimped about the edge of said gasket and pressing the rim of said gasket into said groove for firmly crimping said gasket, and said gasket being formed with a liquid opening and an air opening registering with the liquid opening and air opening of the member to which it is attached.

12. An atomizer comprising a body formed with a bore, a liquid chamber fixed within said bore and comprising a cylindrical wall and an upper end wall, said body being formed with a second bore, a piston mounted for reciprocation within said second bore, the wall of the body between said bores being formed with a passage intercommunicating said bores, said liquid chamber being formed with an external groove communicating with said passage, and said liquid chamber being formed with opening interconnecting said external groove with the upper surface of said liquid chamber, and said end wall being formed with a through passage communicating with the interior of said chamber, a tube having its upper end fixed in said through passage and projecting down into said chamber, a rotary valve above said liquid chamber provided with means to control the passage of liquid from said liquid chamber, and air from said second bore, a ring rotatably mounted on said body to retain said piston in depressed position in one angular position of said ring, and means pivotally linking said valve to said ring to rotate said valve upon rotating said ring to release said piston.

13. An atomizer comprising a body, a liquid chamber within said body, a rotary valve head within said body and provided with means to control passage of liquid from said liquid chamber, an air pump on said body including a reciprocating piston, said rotary valve being provided with means to control passage of air from said pump, means on said body to retain the piston in depressed condition, and means connected to said retaining means for rotating said valve, said last mentioned means comprising an elongated member having one end loosely pivoted to said retaining means and the other end loosely pivoted to said valve, and adapted to rotate said valve upon rotating said retaining means.

14. An atomizer comprising a body, a liquid chamber within said body, a rotary valve head within said body and provided with means to control passage of liquid from said liquid chamber, an air pump on said body including a reciprocating piston, said rotary valve being provided with means to control passage of air from said pump, means on said body to retain the piston in depressed condition, and means connected to said retaining means for rotating said valve, said retaining means comprising a ring rotatably mounted on said body and formed with a slot

and a pin fixed to the piston and adapted to engage said ring in one angular position of the ring, and adapted to pass through said slot in another angular position of said ring.

15. In an atomizer, a body formed with a bore, a plunger mounted for reciprocation therein, said plunger comprising a piston rod, a stem extending from said rod, forming a shoulder, a washer on said stem and engaging said shoulder, a cup-shaped gasket having an end wall through which said stem passes and contacting the washer, said gasket having a downwardly extending cylindrical wall contacting the inner surface of said bore, a member having a sleeve portion surrounding said stem, and having a wall at the upper end of the sleeve contacting the underside of the end wall of said gasket, and an annular wall at the lower end of said sleeve, means to fix said member to said stem, a coil compression spring interposed between said member and the lower end of said bore, and a ring-shaped coil spring surrounding said sleeve portion and pressing the cylindrical wall of said gasket against the inner surface of said bore, a liquid chamber within said body, a rotary valve head within said body and provided with means to control passage of liquid from said chamber, and with means to control passage of air from said bore, rotatable means on said body to retain the piston in depressed position in one angular position of said rotatable means, and means linking said rotatable means to said rotary valve head for rotating said rotary valve head within a limited degree of angular rotation, and for releasing said piston for reciprocation in another angular position of said rotatable means.

16. In an atomizer, a body formed with a bore, a plunger mounted for reciprocation therein, said plunger comprising a piston rod, a stem extending from said rod, forming a shoulder, a washer on said stem and engaging said shoulder, a cup-shaped gasket having an end wall through which said stem passes and contacting the washer, said gasket having a downwardly extending cylindrical wall contacting the inner surface of said bore, a member having a sleeve portion surrounding said stem, and having a wall at the upper end of the sleeve contacting the underside of the end wall of said gasket, and an annular wall at the lower end of said sleeve, means to fix said mem-

ber to said stem, a coil compression spring interposed between said member and the lower end of said bore, and a ring-shaped coil spring surrounding said sleeve portion and pressing the cylindrical wall of said gasket against the inner surface of said bore, said piston rod being of polygonal cross-section, a guide member fixed within the upper end of said bore and formed with a polygonal through opening slidably receiving said piston rod, a ring rotatably mounted on said guide member, releasable means on said guide member for retaining said ring against sliding movement and means on said ring to retain said plunger in fully depressed position in one angular position of said ring and to permit reciprocation of said plunger in another angular position of said ring, a liquid chamber within said body, a rotary valve head within said body and provided with means to control passage of liquid from said chamber, and with means to control passage of air from said bore, and means interconnecting said ring and said rotary valve head for rotating said head upon rotating said ring.

HOBART A. SIMPSON.
